UNITED STATES PATENT OFFICE

103,334

DESIGN FOR A REVOLVING CLOCK

Ralph Magro, Jersey City, N. J.

Application January 23, 1937, Serial No. 67,254

Term of patent 14 years

To all whom it may concern:

Be it known that I, Ralph Magro, a citizen of the United States of America and residing at Jersey City, county of Hudson, State of New Jersey, have invented a new, original, and ornamental Design for a Revolving Clock, of which the following is a specification, reference being had to the accompanying drawing, forming part thereof.

The figure is a perspective view of a revolving clock, showing my new design.

I claim:

The ornamental design for a revolving clock, as shown.

RALPH MAGRO.
